UNITED STATES PATENT OFFICE.

ROYAL R. MILLER, OF CHICAGO, ILLINOIS, ASSIGNOR TO ADOLPH KARPEN, OF CHICAGO,
ILLINOIS.

DAVENPORT-DIVAN.

1,250,614.

Specification of Letters Patent. Patented Dec. 18, 1917.

Application filed February 7, 1913. Serial No. 746,685.

To all whom it may concern:

Be it known that I, ROYAL R. MILLER, a citizen of the United States, and a resident of the city of Chicago, in the county of Cook and State of Illinois, have invented certain new and useful Improvements in Davenport-Divans; and I do hereby declare that the following is a full, clear, and exact description of the same, reference being had to the accompanying drawings, and to the numbers of reference marked thereon, which form a part of this specification.

This invention relates to improvements in davenports of that class set forth in the prior application for patent of Royal R. Miller, for "divan beds," executed on the 12th day of March, 1912, and in which some of the mattress frame sections folded oppositely upon, and were secured wholly to, and secured upon the seat, and in which improved means for supporting and rotating the seat with its load was provided.

The object of this invention is to improve the means for rotatably supporting the seat, and for releasably engaging the folded mattress frame in folded position.

It is also an object of the invention to afford a construction whereby the mattress frame, when extended, is supported at a higher elevation than possible in the said prior construction.

It is, of course, an object of the invention to afford an exceedingly strong, simple and durable device of the class described, easy to operate and affording a short and firm and secure engagement for the seat when the device is closed, and also for the bed, when the mattress frame is fully extended.

The invention (in a preferred form) is illustrated in the drawings, and hereinafter more fully described.

In the drawings:

Figure 1 is a top plan view of a device embodying my invention, with the frame partly broken.

Fig. 2 is an end elevation of the same, with one of the arms and the cam plate removed, and with the seat in normal position.

Fig. 3 is an enlarged similar view, showing the seat inverted preparatory to opening the bed.

Fig. 4 is a reduced view similar to Fig. 3, and showing the mattress frame partly extended.

Fig. 5 is a similar view, showing the mattress frame fully extended.

Fig. 6 is an enlarged elevation, illustrating the relative engagement and position of the cam plate and pivot plate when the seat is at normal and with the seat broken away.

Figs. 7, 8, and 9 are similar views, illustrating the relative movements of the cam and pivoted plates in turning the seat to its full inverted position.

Fig. 10 is a fragmentary section illustrating the locking means for the folded mattress frame.

Fig. 11 is a fragmentary top plan view also illustrating the means for locking the mattress frame in closed or folded position.

Fig. 12 is a fragmentary section taken on line 12-12 of Fig. 10.

Fig. 13 is an enlarged fragmentary section taken on line 13-13 of Fig. 9.

Fig. 14 is a fragmentary section taken on line 14-14 of Fig. 6.

Fig. 15 is a fragmentary detail section on line 15-15 of Fig. 9.

Fig. 16 is a fragmentary detail of one of the legs and illustrates the catch for engaging the same to the mattress frame when in folded position.

As shown in the drawings:

The davenport comprises the end members 1, and back 2, affording the davenport frame. Rigidly secured centrally on each end of said end members 1, is a cam plate 3, comprising a plate cast or stamped to afford near its lower edge a substantially horizontal slot A, extending to near each end of the plate and the lower side or edge of which inclines from its highest point somewhat downwardly to the ends, as shown in Figs. 6 to 9 inclusive.

Opening upwardly and forwardly from said slot or cam groove A, and extending obliquely therefrom is a slot B, one wall of which is afforded by a rib 4, and the other wall by a rounded projection 6, both integral with the cam plate, said rib being connected with said cam plate by an arched web 5, as shown, affording between the main body of the plate and said web beneath the arched portion 5, a cam slot C. Said rib 4, is preferably convex on its rear or upper side and the lower end thereof extends to, but not into the slot A. As shown, the angle of said plate afforded between the for-

ward end of the slot A, and the upwardly and forwardly inclined slot B, is rounded or obtuse to insure clearance by the locking pin and roller hereinafter described.

5 Rigidly secured on the end member 7, of the seat frame, is a pivot plate 8. This extends from a point at the rear of the center of the end of the seat to near the front edge thereof, and rigidly secured thereon near 10 its rear end and lower edge is a pivot 9, on which is secured a flanged roller 10, which fits in the groove A, in the cam plate with the flange thereof lying outside said plate, the end frame member of the davenport, of 15 course, being cut away beneath said plate to afford clearance therefor.

Secured on said pivot plate near the middle and lower edge thereof, is a locking pin 11, on which is secured a roller 12, which 20 tracks in said groove A, as shown in Figs. 6 to 9, and Fig. 13, and serves as a lock for the seat in either of its adjusted positions by engaging beneath the lower end of the rib 4, when the pivot pin and roller are at 25 either end of said slot, and, during the passage of the pivot pin and roller from one to the other end of said slot, acts to ride upwardly in the groove B, and thence downwardly in the groove C, during the 30 inversion of the seat.

As shown also, the cam plate is provided at its forward end with an outwardly struck integral hook or detent 13, adapted to receive therein the edge of the pivot 35 plate, as shown in Fig. 7, and said edge is curved upwardly and forwardly to near the extremity to slide thereover during the return of the seat to normal, and a relatively short straight shoulder 14, is provided at 40 the end of said pivot plate to rest in said detent, as shown in Fig. 6, to afford an additional lock for the seat at normal position.

The mattress frame comprising five articulated sections, is foldable upon said seat 45 when inverted, and at all times, when folded, is supported wholly thereon. Said mattress frame comprises alternate long and short sections, as shown in Fig. 5, and indicated by 16, 17, 18, 19 and 20, and is constructed of angle bars, the ends of the angle bar sections being pivotally engaged together through the webs while the flanges thereof are arranged to abut, as shown in 50 Fig. 1, so that when the mattress frame is 55 extended, the abutting ends of said sections hold the frame as a whole in a common plane.

As shown, the seat frame is provided on its under side, and each rear corner, with 60 a downwardly extending bracket 15, which, when the seat is inverted, as shown in Figs. 3 to 5 inclusive, projects upwardly and outwardly. Rigidly secured by riveting or other suitable means on the under side of the 65 mattress frame sections 14, are downwardly

projecting lugs 21, which may be of any desired length, and which are pivotally engaged on the extremities of said brackets 15, by means of a bolt or pivot pin 22, extending through both, so that, when fully 70 extended, said mattress frame section 17, is elevated a desired extent above the upper end of said bracket.

Rigidly secured at approximately the center of the end of the seat frame and projecting downwardly therefrom, is a grooved guide plate 23, which projects below the seat frame a suitable distance and is provided from a point adjacent the seat frame to the rear end thereof, with a downwardly 80 and forwardly inclining slot D, which, at its lower extremity, is turned horizontally affording a locking offset in the slot. Secured at each end of the mattress frame section 16, is a pin and roller 24, shown in 85 Figs. 1 and 5, and in dotted lines in Fig. 3, said inclined slot in said guide plate and the position of said guide pin and roller on said mattress frame section 16, being such that when the frame is extended, the 90 turning of the short section 17, to a horizontal position acts to swing the long section 16, upwardly thereby moving said pin and roller along the slot and into the short horizontal extension thereof at the extremity 95 of the guide plate to afford a lock.

As shown, a downwardly curved bar or pipe 25, engages at its ends the lug 21, before described, and extends therethrough to afford the pivot in the bracket 15. The 100 second long section 18, is articulated, as before described, at its inner end with the outer end of the short section 17, and in a similar manner the outer long section 20, is articulated with the intermediate long section 18, by means of the short section 19, which articulates with both and the said members of which are connected transversely by means of the downwardly curved bar or pipe 26.

Pivotally engaged at one end with the short frame section 17, is a link 28, which pivotally engages the upper, shorter end of a lever 29, pivoted on the outer end of the intermediate long frame section, and in a 115 similar manner a link 30, pivotally engages the second short section 19, and engages the short upwardly extended end of a lever 31, fulcrumed near the outer end of the outer frame section. The relative lengths of said links and the extended ends of said levers are such that when the bed is opened outwardly, as shown in Fig. 5, said levers 29 and 31 are projected down automatically to afford supporting legs for said sections, but 125 when the bed is folded inwardly from the end by substantially rolling the mattress frame inwardly progressively, said legs fold in closed relation. As shown in Figs. 3, 4 and 5, latches 32, are pivotally engaged to the 130

legs 31, and are held projected outwardly therefrom in the position indicated in Fig. 16 by means of pins 33, which are secured to each latch and bear against the leg. The outer end of said latches 32 are slotted and cut to afford hooks 34, adapted to automatically engage the pins 35, on the respective links when the mattress frame is rolled inwardly and the legs folded in closed relation.

Means are provided for positively locking the mattress frame in folded relation on the seat. For this purpose, spring arms or plates 36, each provided with an inwardly directed hook 37, near its extremity, and an extension 38, for manual engagement beyond the hook is provided on the seat frame, and, when the seat is inverted, extends upwardly upon each side the mattress frame as the same is folded inwardly.

Engaged by metallic straps 39, on the under side of the intermediate long frame sections near the middle thereof, are lateral projections 40, shown as a rod of metal bent to afford a loop projecting beyond said frame members. Said members are pivotally supported in place so that when the bed is extended, as shown in Fig. 5, the same swing downwardly and cannot injure the person. When the bed frame is rolled up or closed upon the seat as shown in Fig. 3, however, the operator engages each of said members or projections and swings the same outwardly, as shown, into engagement with the hook 37, as shown in Figs. 3, 10 and 11.

The operation is as follows:

When the seat is in normal position, as shown in Fig. 2, the folded mattress frame and the bedding are supported wholly upon the seat and beneath the same, and a fall or front board 41, secured at the front of the seat, as shown in Fig. 2, serves to entirely conceal the mechanism supported behind the same. When it is desired to open the bed, the operator engages the front of the seat frame, and pulling the same slightly forward, lifts the seat with the construction supported thereon, which being approximately balanced upon the pivot pin and roller, may be readily inverted, and as the seat is turned over, the locking pin and roller move upwardly in the groove B, in the cam plate, the projection 6, being rounded to prevent the locking roller catching thereon at the beginning of the upward movement.

The pressure applied in inverting the seat, causes the pivot pin and roller to move outwardly to near the forward end of the slot A, and having passed the highest point therein (at which time the locking roller passes over the upper end of the rib 4, and engages on the opposite side thereof in the groove C), the movement is continued until the locking roller reaches the lower end of

the rib 4, permitting the pivot roller to move downwardly to the forward extremity of the slot A, and the pivot roller to engage beneath the end of the rib 4. The seat is now locked in inverted position and cannot be moved except reversely and by first pushing the seat slightly inward to clear the locking roller from the lower end of the rib 4.

The latches or projections 40, are now released by pressing on the extended end 38, of the spring hooks and the outer sections of the bed frame are swung outwardly and downwardly, as illustrated in Figs. 4 and 5, thus projecting the legs 29 and 31, into supporting position, as shown in Fig. 5, and acting conjointly as a lever to swing the short sections 17, upwardly, thereby elevating and pushing the long section 16, inwardly, moving the guide rollers upwardly in the inclined groove in the guide plate to the top thereof and into supporting position. In this position the bed is fully extended for use. The fall or front board 38, and the upholstering of the back of the davenport 90 serves as a head-board for the bed to assist in holding the bedding in place.

The closing of the bed is effected in the same manner, the sections folding or rolling inwardly, and, as the same swing past the position shown in Fig. 4, the hook 34 on the latches 32, engage the pins 35, and the short section 17, swings to substantially the position shown in Fig. 3, thus drawing the long section 16, outwardly and downwardly to a position close against the seat frame. The projections 40 are again engaged upon the spring hooks, and the seat may be returned to normal. During the return to normal, the edge of the pivot plate engaging in the hooked detent afforded on the front end of the cam plate, is guided thereby, and substantially locked from any movement away from said cam plate.

Of course, I appreciate that numerous details of the construction may be varied. I have illustrated and described but a preferred construction, and I therefore do not purpose limiting the patent granted on this application otherwise than necessitated by the prior art.

I claim—

1. A davenport comprising a revolving seat, a mattress frame pivotally secured to the seat consisting of sections pivotally connected, links pivoted to some of said sections, legs pivotally connected to the links, pins secured to some of said links, latches secured to some of said legs projecting outwardly to engage said pins to hold the outer frame sections rigidly together and pins secured to said latches for holding the same in their projected position.

2. In a device of the class described a rotatable seat frame, a mattress frame thereon

comprising inner, intermediate and outer articulated sections adapted to be folded or rolled upwardly and inwardly from the outer end together with its mattress, legs 5 pivotally mounted on said intermediate and outer sections, links connecting said legs with said intermediate and outer sections, hook latches pivotally mounted on said outer legs to interlock with said intermediate sections to hold the mattress frame folded, a pin secured on one end of each of said latches adapted to contact the respective outer legs to hold said latches in a projected position to permit engagement with said 10 intermediate sections, brackets rigidly secured on the seat frame with which the intermediate sections of the mattress frame are connected, and means elevating the mat- 15

tress frame above said brackets embracing a projection on said sections affording the 20 connection between the brackets and the same.

3. A davenport comprising a revoluble seat, articulated mattress sections connected to the seat, pivotally connected links and 25 legs pivoted to the mattress sections and co-acting members secured on said legs and links for rigidly fastening part of the mattress sections together when folded.

In testimony whereof I have hereunto 30 subscribed my name in the presence of two subscribing witnesses.

ROYAL R. MILLER.
